UNITED STATES PATENT OFFICE

145,659

DESIGN FOR A COMBINATION DESK AND SEAT

James D. Covington, Dallas, Tex., assignor to Hill-
top Manufacturing Company, Cockrell Hill,
Tex.

Application October 15, 1945, Serial No. 122,858

Term of patent 7 years

(Cl. D33—11)

To all whom it may concern:

Be it known that I, James D. Covington, a citizen of the United States, residing at Dallas, in the county of Dallas and State of Texas, have invented a new, original, and ornamental Design for a Combination Desk and Seat, of which the following is a specification, reference being had to the accompanying drawing, forming part thereof.

Figure 1 is a front perspective view of a Combination Desk and Seat showing my new design.

Figure 2 is a top plan view thereof, and
Figure 3 is a front elevational view thereof.

I claim:

The ornamental design for a combination desk and seat, as shown.

JAMES D. COVINGTON.
